UNITED STATES PATENT OFFICE

PAUL MARIE EUGÈNE LÉOTARD, OF PARIS, FRANCE

STEAM EJECTOR OF VACUUM BRAKES

Application filed December 18, 1928, Serial No. 326,837, and in Germany January 7, 1928.

The combined ejectors of automatic vacuum brakes should maintain a substantially constant vacuum in the train pipe and in the brakes of the vehicles. With this object in view, the installations comprise in conjunction with the main ejector a small ejector the supply of steam to which is continuous and which is intended to maintain the vacuum produced by the main ejector, and one or more small auxiliary ejectors which operate when the preceding ejector is insufficient viz. when leakage occurs in the train pipe. The arrangement of the small ejectors is of great importance; a defective combination of the discharge nozzles may produce disturbances and cause losses of energy to such an extent that only a very small increase in vacuum may be obtained at the expense of an increase in consumption of steam following the setting in operation of a small auxiliary ejector.

In certain constructions the main ejector and an auxiliary ejector are disposed symmetrically in relation to the discharge outlet. This arrangement is unsatisfactory having regard to the disproportion in the energy of the corresponding jets of steam. In other constructions the small continuously operating ejector and the small auxiliary ejector are disposed on the same side of the main ejector. This arrangement does not however give good results, the want of symmetry between the said small ejectors producing disturbances in the discharge.

The ejector forming the subject of the present invention has for its object to avoid these disadvantages. Characteristic of the invention is that the small continuously operating ejector and the small auxiliary ejector are disposed symmetrically in relation to the main ejector and are inclined at a very small angle to the latter. The steam is thus discharged without disturbances and the optimum use of the steam obtained having regard to the vacuum to be obtained.

As an example and for purposes of illustration, a preferred embodiment of the invention is shown in the drawings, wherein:

Figure 1 is a section of the apparatus through a plane common to the axes of the

cones of the main ejector, of the small ejector and of the auxiliary ejector.

Figure 2 is an enlarged sectional view showing the air-collector and the means whereby said collector is placed in communication with the atmosphere through the instrumentality of the steam inlet valve and the small ejector.

Fig. 3 is an additional view of the ejector showing the operating handle and associated parts.

The main ejector comprises an annular steam inlet passage *a* and a central steam jet *d*. The small continuously operating ejector comprises an annular steam inlet passage *b* and the small auxiliary ejector has similarly an annular steam inlet passage *c*. In addition each has a central steam jet which is not shown in Fig. 1, but is shown in Fig. 2. The main ejector *a*, *d* serves to empty the train pipe of the vehicle after brakes have been applied; the small continuously operating ejector *b* is intended to maintain the vacuum in the train pipe while the small auxiliary ejector *c* is set in operation if the preceding ejector is insufficient e. g. to compensate for leakage in the train pipe. The discharge nozzles *e* and *f* of the two small ejectors are symmetrical in relation to the axis *x*, *y*, of the main ejector and form with the latter a very small angle. They connect with the annular space between the discharge nozzle *g* of the main ejector and the outlet passage *h*. The steam jets of the two small ejectors are therefore subjected in their passage only to a small deviation so that the fact that they unite around *g* does not produce any disturbances.

The small ejectors *b* and *c* are provided with solid jets; moreover the admission of steam to the jets *i* is regulatable by means of valves *j*. This arrangement permits of obtaining a high vacuum when the valves are open or a great saving in steam when they are closed. The ejector may thus work according to requirements and under the best conditions.

It is known that the air is drawn from the train pipe through the medium of an air collector. The latter is shown at *o* in Fig. 3.

When the supply of steam to the small ejectors is interrupted it is necessary to prevent the vacuum from being maintained in the collector because in case of leakage from the retaining valves there would be produced in the collector an accumulation of water which might be carried into the train pipe and might damage the rubber joints notably the rolling rings of the brake cylinders.

10 The operation of the ejector forming the subject of the present invention provides automatic protection. When the handle *l* is turned to close the steam inlet valve *k* to the small ejectors, the channel *s* in the rod *m*, 15 *n* connects the two adjacent conduits *q*, *r* the former of which has an enlargement *p* in communication with the atmosphere and the second of which is connected with the collector *o*. The collector is thus filled with air. When the valve *k* is opened the rod *m*, 20 *n* being retracted interrupts communication between the conduits *q* and *r*. Rubber rings *t* disposed in grooves on each side of the passage *s* prevent any escape of air.

25 The ejector described has many advantages over ejectors of existing construction. In view of the symmetry of the small ejectors, the powers of which are of the same order of magnitude, disturbances are very much reduced compared to those produced by assymetric arrangements. Moreover this symmetry permits of giving to the small ejectors the optimum angle of inclination. The presence of valves controlling the inlet to the central steam jets of the small ejectors permits regulation of the vacuum additional to that already obtained by the operation of the main valve. Finally the connection of the air collector with the atmosphere and the 30 interruption of this connection are obtained by a very simple means which do not involve the interposition of cams and levers.

Having now particularly described and ascertained the nature of my said invention and in what manner the same is to be performed, I declare that what I claim is:—

1. A combined ejector for automatic vacuum brakes, comprising a main ejector, a continuously operating small ejector and a 35 small auxiliary ejector wherein the small ejectors are symmetrically disposed with relation to the main ejector and form with the latter a very small angle.
2. An ejector as claimed in claim 1 wherein each of the small ejectors has a central nozzle provided with a regulating steam inlet valve independent of the main inlet valve.
3. A combined ejector for automatic vacuum brakes, comprising a main ejector, a 40 continuously operating small ejector, a small auxiliary ejector, both small ejectors being disposed symmetrically relatively to the main ejector and at a small angle thereto, a central nozzle provided on each of the small 45 ejectors, a steam regulating inlet valve in

each nozzle, a stem on said valves having a suitable channel therein, and an air collector, communication between the air collector and the free atmosphere being effectuated by means of said channel controlling the junction of two ducts leading to the air collector and atmospheres, respectively. 70

In witness whereof I have hereunto set my hand.
